UNITED STATES PATENT OFFICE.

SAMUEL C. SIMS, OF STERLING, ILLINOIS.

DENTAL CABINET.

973,573.

Specification of Letters Patent. Patented Oct. 25, 1910.

Application filed August 25, 1909. Serial No. 514,521.

To all whom it may concern:

Be it known that I, SAMUEL C. SIMS, a citizen of the United States, residing at Sterling, in the county of Whiteside and State of Illinois, have invented a new and useful Dental Cabinet, of which the following is a specification.

My invention has reference to dental cabinets, such as are commonly used by dentists and other artisans for holding tools and implements conveniently to their work.

The chief purpose of my invention is to provide a cabinet containing a plurality of drawers or trays, such cabinet being vertically adjustable, so that said trays can be severally brought into operative position, and retained therein. The trays are also supported in such a manner as to be capable of movement outwardly from the cabinet, and away therefrom to a point convenient for the use of the tools or material contained therein.

An additional feature of my device consists in the provision of a compartment to be supplied with disinfecting material, which compartment will be capable of automatically communicating with the tray compartments when the trays are in place therein.

Other features and advantages of my invention will more fully appear in the following specification, reference being had to the drawings accompanying the same, in which:

Figure 1 is a front elevation of my invention. Fig. 2 is a side view thereof, with one of the side plates removed. Fig. 3 is a plan view of one of the tray receptacles, with the tray in place therein. Fig. 4 shows the two lower compartments of the cabinet, in cross-section. Fig. 5 is a detail, showing one of the bracket-arms, in perspective.

Corresponding parts are referred to by similar numerals of reference throughout the several figures.

The device has a supporting frame, comprising a base-plate 1; a pair of box-pillars 2, mounted thereon, and surmounted and united by a top 3.

4 represents a cabinet, or case, capable of vertical movement between the pillars 2, and supported at each side by means of a plate 5, secured to the cabinet, and attached to which plate is a cord 6, passing upwardly over pulleys 7 in the upper part of the frame, and provided at its ends with weights 8.

Mounted on each plate 5 are two pair of anti-friction rollers 9, which engage the opposite edges of a channel 10 in the inner wall of the pillar 2, and which, in conjunction with the weights 8, which counterbalance the weight of the cabinet, render such cabinet capable of being easily raised and lowered. This may be accomplished by means of a handle 11, attached to the lower front side thereof.

The cabinet 4 is subdivided into a plurality of compartments 12, each of which is provided with a tray 13, freely supported therein by means of a bracket-arm 14, hingeably attached at one front corner of the cabinet, and an arm 15, hingeably connected with the arm 14, and to the free end of which the tray 13 is hingeably secured, at one of its rear corners. By this means the tray can be entirely removed from the cabinet, and supported at some distance therefrom. See Fig. 3, broken lines. The arms 14 and 15 are of such length that they will each occupy a limited space at one side of the tray 13, when such tray is fully inserted within the cabinet.

In rear of the compartments 12 is a chamber 16, separated from said compartments by a partition 17, but capable of communicating with said compartments independently by means of doors 18, in the partition 17, and adapted to be forced open by fingers 19 on the inner ends of the trays 13, when such trays are inserted completely within the compartments 12. Upon the doors 18 being disengaged by the fingers 19 such doors are closed by means of springs 20.

The chamber 16 is provided with a suitable sterilizing material, and it will be obvious that so long as one of the trays 13 is in position in its compartment the fumes of such sterilizing agent will permeate thereto, and that upon the withdrawal of such tray from its compartment, the means of communication between such compartment and the fumigation chamber will be automatically closed, preventing the escape of the fumes. The material may be introduced into the chamber 16 by means of a drop door 21 at the lower end thereof. To render the operation of this part of the device successful it is essential that all parts of the cabinet shall be constructed as nearly air-tight as possible.

The trays 13 may be furnished with aux-

iliary trays or shelves 22, by which means the instruments which have been used may be separated from those which have not been.

In use, the device is located on the opposite side of the operator from the patient, and facing him. The cabinet 4 is then stationed at a suitable height for the use of the particular tray in which are the instruments which are being used, it being preferred to have the different trays provided with instruments for different classes of work. The tray which is in use is drawn outwardly from the cabinet, and to a point where the contents thereof can be conveniently reached. When that part of the operation which calls for the use of the instruments in such tray is completed, the tray is returned to its compartment, the cabinet 4 raised or lowered to bring the tray which will be next employed to the desired height, and such last-named tray brought to an operative position. The tools which have just been used can then be removed and cleansed by the operator's assistant.

What I claim as my invention, and desire to secure by Letters Patent of the United States, is,

1. A device of the class named, comprising a supporting frame; a cabinet, vertically adjustable in said frame, and containing a plurality of tray compartments, one above another; jointed bracket-arms, pivotally supported in said compartments, and capable of movement outwardly therefrom; and a plurality of trays, hingeably supported by said bracket-arms.

2. In a device of the class named, the combination of a supporting frame; a cabinet, vertically adjustable in said frame, and containing a plurality of tray compartments, one above another; a plurality of trays, swingingly supported in said compartments, so as to move freely outwardly and away

therefrom; a sterilizing chamber, adapted to communicate independently with said tray compartments; and means for opening communication between said chamber and either of said compartments upon the insertion of the tray therein.

3. A device of the class named, comprising a pair of suitably supported pillars, provided with vertical channels in their inner faces; a cabinet, vertically movable between said pillars, and provided on its sides with guide-means engaging said channels; and means for counterbalancing the weight of said cabinet.

4. In a device of the class named, a pair of suitably mounted box-pillars, provided in their inner faces with vertical channels; a cabinet, vertically movable between said pillars, and provided on its sides with guide-means engaging said channels; a plurality of trays, supported in said cabinet; a plurality of weights, vertically movable within said pillars; and means for connecting said weights with said cabinet, to counterbalance the weight thereof.

5. In a device of the class named, a cabinet containing a plurality of tray compartments; a plurality of bracket-arms, pivotally supported at one front corner of said cabinet; a plurality of arms, hingeably connected with said bracket-arms; and a plurality of trays, pivotally supported at the free ends of said last-named arms, and capable of horizontal movement outwardly and away from said cabinet, said supporting arms being in the same planes with the trays supported thereby, and adapted to fold against the sides thereof, when the trays are in place in the cabinet.
